TOOL SLIDE

Clarence D. Pulsifer, Farmington, Conn., assignor
to The New Britain Machine Company, New
Britain, Conn., a corporation of Connecticut

Application December 12, 1946, Serial No. 715,896

3 Claims. (Cl. 308—3)

1

My invention relates to a tool slide or the like and more particularly to means for adjusting the fit between two relatively slidable members.

Tool slides and the like frequently employ a dovetail slot and dovetail for slidably engaging a tool slide or the like with its base. It is common practice to make the dovetail and slot on an angle of about 45°. A lesser angle is in many cases much more desirable, but with a lesser angle of contact there is great likelihood that the slide will stick upon the application of substantial lateral or twisting force. Some dovetail slot connections have included an adjustable gib for varying both the lateral and the vertical fit between the dovetail and its slot. However, where both the lateral and vertical fits are determined by the gib or gib, there is also likelihood of sticking or binding upon application of a heavy lateral or twisting force, and this tendency to binding or sticking becomes more pronounced as the angle of the dovetail and the slot is diminished.

It is an object of my invention to provide improved means for adjusting the fit between two relatively slidable members connected by means such as a dovetail slot means.

It is a further object to provide a slidable connection between two members such as a tool slide and its base, wherein the tendency to bind or stick is reduced to a minimum.

It is a further object to provide a slidable connection between a pair of members so arranged that the lateral fits and vertical fits are separately adjustable.

It is a further object to provide improved means for adjusting the lateral fit between a pair of relatively slidable members connected by a lug and slot type of connection.

It is a further object to provide improved means for adjusting the vertical fit between two relatively slidable members connected by means of a slot and lug type of connection. In general, the object is to provide an improved sliding connection between a tool slide or the like and its base.

Broadly speaking, my invention may be embodied in a slide connection involving slots and lugs slidable in such slots. Such a connection may be, though it is not necessarily, embodied in a dovetail slot connection. The lateral fit between the two relatively slidable members, in accordance with my invention, is determined by improved means independently of the vertical fit between the two members; and the vertical sliding fit is determined independently of the lateral fit. In the preferred form, the slide and its base are so arranged that the points or zones of sliding contact are separated from each other so that spaced point or zone contact is obtained and there is little or no tendency for the slide and its base to bind upon the application of heavy lateral or twisting forces.

2

The invention, in the illustrative form shown, is embodied in a dovetail slot type of connection.

In the drawings which show, for illustrative purposes only, a preferred form of the invention:

Fig. 1 is a fragmentary top plan view of a slide and base illustrative of the invention;

Fig. 2 is a sectional view, taken substantially in the plane of the line 2—2 of Fig. 1;

Fig. 3 is an enlarged, fragmentary, sectional view, taken substantially in the plane of the line 3—3 of Fig. 1;

Fig. 4 is an enlarged, fragmentary, sectional view, taken substantially in the plane of the line 4—4 of Fig. 1.

In the illustrative form shown, one of the slid-
able members has a dovetail, while the other
member has a dovetail slot. As illustrated
specifically, the base 5 is provided with a dovetail,
while the slide 6 is provided with a dovetail slot
interfitting with the dovetail. The usual com-
mercial incline of a dovetail is about 45°, but by
reason of my invention I am able to employ a
dovetail and slot having a substantially lesser
angle as indicated at 7, and that angle may be
reduced still more.

The dovetail has opposed outwardly turned
lugs 8—8, which in the preferred form have flat
lateral bearing surfaces 9—10. The flat longi-
tudinal bearing surface 9 is slidably engaged
with a bearing surface 11, preferably also flat,
and in the preferred form the bearing surface 11
in the bottom of the dovetail slot is relieved, as
indicated at 12, so as to provide spaced apart
bearing points or bearing zones between the dove-
tail and slot, as indicated at 13—13. The dove-
tail at the opposite side 10, in the preferred form,
does not engage the adjacent bottom of the dove-
tail slot directly as does the side 9, but engages
adjustable means for forcing the dovetail laterally
and adjusting and determining the lateral fit be-
tween the dovetail and the slot.

In the form illustrated, I employ adjustable
shoe means between the right-hand side of the
dovetail and the slot, and such a shoe 14 may
be carried in a recess 15 in the bottom of the
dovetail slot. The shoe 14 may be adjusted as
by means of a screw 16, which may be locked in
adjusted position as by means of a lock nut 17.
I preferably employ two such shoes spaced longi-
tudinally of the dovetail slot connection, as is
clearly indicated in Fig. 1, and since both shoes
and their adjustment are identical or quite simi-
lar, a description of the one will suffice for both.
It will be seen, then, that what I term the lat-
eral or sidewise fit between the dovetail and the
dovetail slot may be determined by the adjust-
ment of the shoes 14 and when both shoes (when
two are employed) are adjusted, there will be
spaced apart bearing surfaces which will tend to
avoid any binding or substantial resistance to
longitudinal sliding.

What I term adjustment of the "vertical fit" of the slide relatively to its base is determined by means quite independent of the shoe means 14 for determining "lateral fit." The vertical fit adjustment in accordance with my invention is determined by laterally adjustable gib means secured to the slide and having a bearing thereon and on the dovetail so arranged that lateral movement will cause a tighter or looser fit between the dovetail and its slot and thus determine the vertical fit of the lugs in the slots. As illustrated, the slide 6 carries two adjustable gibs 18-19, which may be and preferably are duplicates of each other so that only one need be described. The bearing face 20 of each gib is arranged at an angle to the bearing surface 21 so that when the gib is adjusted laterally, the face 20 will move into tighter or looser engagement with the corresponding face on the lug 8. As illustrated, where the bearing face 20 is at an angle, the face 21 may be horizontal (in a relative sense, of course).

The gibs 18-19 are secured in position as by means of screws 22 which pass through oversize slots in the slide while the heads are seated in a counterbore and the screws are threaded into the gibs as shown at 24. A sufficient number of such screws 22 are employed so as to hold the gibs with the required security and rigidity. As stated, the gibs are adjustable so as to vary the vertical fit between the dovetail and the slots. The preferred form of adjustment is by means of a cam or eccentric so that very fine gradations of adjustments may be made. As illustrated each slide is provided with screws 25 having eccentrics 26 at the bottoms which fit in slots 27 in the gibs. Thus when the gib securing screws 22 are loosened, the adjusting screws 25 may be turned and the eccentrics 26 will urge the gibs into just the desired positions of adjustment. During the adjustment, the holding screws 22 may move with the gibs because of the oversize holder 23 as will be understood. When the gibs have been moved to just the desired positions of adjustment so as to secure the exact vertical fit desired the holding screws 22 are tightened so as to hold the gibs in position.

It will thus be seen that I have provided means for determining the lateral fit of the slide and its base and have provided entirely independent means for determining the vertical fit. Since in the preferred form the points or zones of contact between the sides of the dovetail and the bottoms of the dovetail slot are at spaced apart points and since the lateral fit and the vertical fit are determined independently of each other, it will be clear that there will be little or no tendency of the slide to bind during its sliding movement on the base. Furthermore, because of the independent adjustments there will be no necessity for the expensive scraping in of bearing surfaces and therefore hardened slide surfaces (which cannot be scraped) may be employed. With hardened surfaces there will be little or no wear and such wear as does occur may be readily compensated for by the simple adjustments of lateral and vertical fit.

The invention has been described as embodied in a dovetail slot type of connection but it is to be understood that the principles of the invention are applicable to other forms of lug and slot connections.

While the invention has been described in considerable detail and a preferred form illustrated, it is to be understood that various changes may

be made within the scope of the invention as defined in the appended claims.

I claim:

1. In a device of the character indicated, a member having a dovetail slot, a member having a dovetail relatively slideable in said slot, one side of said dovetail and the adjacent side of said slot having sliding lateral bearing engaging surfaces at relatively widely separated points and being free laterally of each other intermediate said points, and the opposite side of said dovetail and the adjacent side of said slot having adjustable shoes between the lateral sides of said dovetail and slot, said shoes being relatively widely separated and being located generally opposite said first-mentioned lateral bearing engaging surfaces, whereby said dovetail and slot will be in sliding bearing engaging contact at two widely separated points at each side to minimize sticking of said dovetail in said slot, and an adjustable gib means forming a part of said slot and serving to hold said dovetail in said slot.

2. In a device of the character indicated, a member having a dovetail slot, a member having a dovetail to fit in said slot, at least one side of said dovetail slot being defined by an adjustable gib, said gib having a horizontal bearing surface on the member carrying said gib, vertical screw means securing said gib to its member, means for adjusting said gib laterally and horizontally, said gib and the underside of said dovetail having sliding surfaces at a small angle to the horizontal whereby horizontal and lateral adjustment of said gib will vary the vertical fit of said dovetail in said dovetail slot, said dovetail and said slot at one side having a horizontally adjustable shoe providing a sliding engagement between said dovetail and said slot, and adjusting means to move said shoe horizontally to adjust the lateral fit between said dovetail and said slot, while leaving the vertical adjustment unaffected.

3. In a device of the character indicated, a member having a dovetail slot, a member having a dovetail relatively slideable in said slot, said dovetail slot being defined by at least one side by an adjustable gib, said gib and the coating surface on said dovetail being inclined at a small angle to the horizontal, a plurality of eccentrics between the member having the slot and said gib for adjusting the gib laterally of the slot, screws for clamping said gib to its member, whereby lateral adjustment of said gib will determine the vertical fit of said dovetail and slot and said gib will be held in adjusted position by said clamping screws, a shoe engageable laterally between one side of said dovetail and the adjacent side of the slot, and means for adjusting the position of said shoe to determine the fit of said dovetail laterally in said slot.
